UNITED STATES PATENT OFFICE.

ARNALDO CARPINETI, OF BUENOS AIRES, ARGENTINA.

HIGH-DUTY PETROLEUM STOVE.

Application filed January 2, 1926; Serial No. 79,059, and in Argentina June, 1925.

The present invention relates to improvements in high duty petroleum stoves such as are used in cooking great quantities of food for large gatherings of people, and is particularly useful in cantonments, field kitchens, etc.

The invention relates particularly to a petroleum burning cooking stove in which a plurality or battery of cooking kettles are provided with facilities also for dry cooking such as baking, and for the heating of water for supplying the cooking vessels or for other purposes.

The invention primarily relates to a stove of the character indicated in which the burners are located beneath the level of the ground or at least below the level of the floor or base upon which the cooking vessels rest, and the heating of said vessels is done through flues for the products of combustion of the burners, which flues are arranged in heat interchanging relationship with the cooking kettles.

Several modifications of the invention are shown in the drawings, the preferred form which will be described most in detail, being shown in Figures 1 to 3 inclusive.

Referring to the drawings:

Figure 1 is a longitudinal vertical section through a cooking stove representing the preferred form of the invention.

Figure 2 is a horizontal view partly in plan and partly in section through a part of the stove representing one of the batteries of kettles, taken in a plane intermediate the top and bottom of the wells which surround the kettles.

Figure 3 is a vertical cross section taken in a plane at right angles to the plane of Figure 1 in the median plane of said figure.

Referring now in detail to the several figures, the numeral 13 represents a base which may be of any suitable material and is preferably built below the level of the ground so that the cooking vessels indicated at 14 and which due to their great size, are quite heavy, are conveniently close to the ground.

The base 13 is provided with combustion chambers 8. In the present illustrative embodiment of the invention there are two batteries of cooking kettles, four in each battery, one battery being clearly shown in Figure 2, and one combustion chamber furnishes heat for each battery, there being two combustion chambers. These chambers communicate by

means of the flues 1 with spiral flues or passages 5 forming the walls of wells in which the cooking kettles are adapted to be seated. In the present instance there are four flues for each combustion chamber, each leading to the spiral passage surrounding one of the wells.

The spiral flues finally discharge through manifolds 16 shown in Figure 1, said flues being provided, if desired, with dampers, controlled by the handles 4.

Each combustion chamber is furnished with a burner 9, said burner being supplied with fuel and with air forming a combustible mixture. The burners may be ignited in any suitable manner by means not shown. The supply of fuel to the burners is conveniently controlled from a point adjacent the chamber by a hand wheel 11 connected with the burners through a suitable train of mechanism 12.

The two burners and the batteries of cooking kettles provide facilities for the cooking of a great quantity of food and in quite great variety. However it is desirable if not essential, to have some means for dry cooking such as baking. For this purpose an oven 18 is provided. This oven is preferably located between the batteries of cooking kettles and is surrounded by a jacket in which are baffles forming a tortuous passage 7 for the heated combustion products. The oven is preferably provided with a separate burner 19 shown in Figure 3 operating in a combustion chamber 20 which as shown, discharges the combustion products into the top of the flues surrounding the oven from which said products of combustion after passing the baffles as shown in Figure 3 discharge through a conduit 17 to any suitable outlet not shown, for instance a chimney.

One of the salient features of the invention is the fact that the fuel supply for those burners which serve the batteries of kettles is pre-heated by the burner which is utilized for heating the oven. This will appear from Figure 3 in which a fuel tank 21 is shown below the combustion chamber and within a heated space back of the oven. This tank communicates by suitable conduits with the respective burners 9 as well as the burner 19 which heats the oven.

The burner 19 also heats a plate 20 which may be used for purposes of surface cooking, such as frying.

A water tank 27 shown in Figure 2, is ar-

ranged above each combustion chamber in the path of the ascending products of combustion.

While I have in the above specification described what I believe to be preferred and practical embodiments of my invention, it is to be understood that the specific details of construction are not limitative but merely by way of example, and that the invention may 10 be expressed in other ways if desired.

What I claim is:

A high duty petroleum cooker comprising a base plate, said cooker being provided with combustion chambers below said base plate, 15 oil burners arranged to direct a flame inwardly toward the middle of said cooker, within said combustion chambers, a water heater associated with each combustion chamber superposed with respect to a flue communicating 20 with said combustion chamber, branch flues of approximately equal length communicating with said combustion chamber and symmetrically arranged with respect to said

water heater, a well associated with each branch flue comprising an annular cylindrical jacket having a spiral baffle between the walls thereof and being in communication with said branch flues, said wells being each adapted to receive a cooking kettle, a jacketed oven 25 symmetrically arranged with respect to said combustion chambers, a hot plate above the oven, an auxiliary combustion chamber directly beneath said hot plate, an oil burner 30 for delivering heated combustion products to said chamber, the latter communicating with the space within said oven jacket, a fuel tank 35 in conductive relation to the heat generated within said auxiliary combustion chamber and the heat of said cooker conserved by the specified disposition of the other sources of 40 heat, and exhaust flues located directly beneath said oven for carrying away the spent combustion products.

Signed at Buenos Aires, Argentine Republic, this 1st day of July, A. D. 1925.

ARNALDO CARPINETI.
